UNITED STATES PATENT OFFICE.

GEORGE W. GARDANIER, OF NEW YORK, N. Y.

TELEGRAPHIC RELAY.

SPECIFICATION forming part of Letters Patent No. 316,956, dated May 5, 1885.

Application filed March 24, 1884. (No model.)

To all whom it may concern:

Be it known that I, GEORGE W. GARDANIER, a citizen of the United States, and a resident of New York, in the county of New York and 5 State of New York, have invented certain new and useful Improvements in Telegraph-Repeaters, of which the following is a specification.

The invention relates to an improvement in 10 telegraph-repeaters for automatically repeating signals from one single circuit into another, and vice versa; and it consists, essentially, of two ordinary Morse relays, their armatures closing their respective local circuits on the 15 back contact, and two transmitters, each having a rear spring-contact and, adjacent to the upper side of the forward end of the lever, a fixed contact or one without spring-action.

In the accompanying drawing I illustrate 20 my invention, and in said drawing T and T' respectively denote the transmitters; R and R', respectively, the relays, and B B' the local batteries. The lever of the armature T has upon its upper surface the insulated post A, 25 upon which is secured one end of the circuit-spring C, the other end of which extends beyond the rear end of the lever and terminates above the contact D. Upon the lower side of the lever of transmitter T is applied a retractile spring, E, by which, when the line is idle, the rear end of the lever is depressed and the circuit-spring C thrown in contact with the stop D, this being the condition of the transmitter when open. The front end of the lever 30 of transmitter T moves between the stops or contacts F G, and below said front end is the usual electro-magnet, f. The transmitter T' is similar in all essential respects to the transmitter T, it being furnished with the circuit-spring contact H on its rear end, the stationary 35 stops I J, between which its front end moves, and the electro-magnet K, by which it may be opened or closed. The transmitter T' is supplied also with the usual retractile spring, L, 40 and below the outer end of the circuit-spring H is a stationary stop, M. The relay R is the ordinary Morse relay, consisting of the electro-magnet N and armature O, the upper end of which moves between the resting-contact P and 45 working-contact Q, which latter is on what is known as the "back side" of the armature. 50

The armature O is provided with a retractile spring, S, by which it is retained against the contact Q in the absence of a current through the electro-magnet N. The relay R' is the 55 same as relay R, and its various parts are denoted by the same letters primed, which represent portions of like name in the relay R. The locals are lettered, respectively, V, W, X, Y, x, and y, the wire V passing from the stop 60 F to one side of the electro-magnet K, that lettered W from the stop I to one side of the electro-magnet f, that lettered X from the armature of transmitter T to the local battery B', and thence to the armature O', while the wire 65 Y extends from the armature of transmitter T' to the local battery B, and thence to the armature O. The wire x passes from the stop Q to the electro-magnet f, and the wire y from the stop Q' to the electro-magnet K. The main 70 line from, say, the east, lettered a, connects with the circuit-spring C, and is continued thence by the wire b to the electro-magnet N', and from that to the battery and earth by a wire, d. The main line to the west is in electrical connection with the circuit-spring H, and also, when the transmitter T' is closed, 75 with the electro-magnet N, by means of the stop M and wire e. From the electro-magnet N a wire, g, passes to the battery and earth. 80 The electric impulses in the wire a during the transmission of signals from the east pass into the wire b through the spring C and stop D, and thence into the electro-magnet N' and earth, the effect of their passage into the electro-magnet N' being to operate the armature 85 O', and to open or close the local circuit consisting of the wires y V X, battery B', and electro-magnet K, which operates the transmitter T' to make and break the main-line circuit at 90 M and the local circuit of transmitter T at I, the effect being that the message transmitted over the wire a from the east will be repeated into the western circuit by the operation of the transmitter T'. The relay R being in the main-line circuit, which is opened at M by the movement of the transmitter T', would tend to close the local circuit of transmitter T at Q, were it not that this action has been prevented by the lever of transmitter T' breaking the local circuit of transmitter T at the contact I. The transmitter T is thus prevented from interfer- 95 102

ing with the operation of repeating, which is being performed by the transmitter T'. The signals from the west will be repeated into the eastern circuit in the same manner as those from the east are repeated by the transmitter T' into the western circuit, the two parts of the apparatus being duplicates. When the signals are from the west, the main-line circuit is through the wire e, electro-magnet N, and wire g, to the earth, while the local circuit is through wire W, electro-magnet f, wire x, local battery B, and wire Y. The effect of the relay R' during the transmission of signals from the west is the same as that of the relay R while messages are coming from the east. It would tend to close the local circuit of the transmitter T' at Q', were this not prevented by the fact that the local circuit of said transmitter T' has been just previously broken at F by the lever of transmitter T. During the movement of the transmitter T (and the same is true of transmitter T') the contact at F is permitted to be broken immediately before the main circuit at D is broken by reason of the circuit-spring C, which will remain against the stop D until after the front end of the transmitter-lever has broken its contact with the stop F. It will thus be noted that one transmitter will not create a disturbance while the other is repeating.

What I claim as my invention, and desire to secure by Letters Patent, is—

1. A telegraph-repeater consisting of a transmitter and relay for each of the main-line cir-

cuits with local circuits, the transmitters each being arranged with contacts to directly break the local circuit of the other before the main-line circuit is broken, whereby one transmitter is kept idle while the other is operating, substantially as set forth. 35

2. In a telegraph-repeater, the relays, the armatures of which are arranged to close their respective local circuits on the back contact, in combination with the transmitters having a spring-contact at one end and a fixed contact 40 at the other, and with local and main-line circuits, substantially as set forth. 45

3. In a telegraph-repeater, the combination of the transmitters TT', having circuit-springs C H, respectively, with local and main-line circuits and relays R R', whose armatures act on the back contact to close their respective local circuits, substantially in the manner described. 50

4. In a telegraph-repeater, the transmitter, relays, and local and main-line circuits, the armature of the relays operating their respective transmitters on the back contact, and one end of each transmitter being in and adapted to open and close the local circuit of the other transmitter, substantially as set forth. 55

Signed at New York, in the county of New York and State of New York, this 20th day of March, A. D. 1884.

GEORGE W. GARDANIER.
